UNITED STATES PATENT OFFICE

1,939,538

PIPE HANGER FOR HARDENING ROOMS

Victor Buhr, Larchmont, N. Y., assignor to Equity Construction Company, New York, N. Y., a corporation of New Jersey

Application May 17, 1932. Serial No. 611,884

3 Claims. (Cl. 248—31)

My invention relates to pipe hangers and to a building construction embodying a pipe hanger. More particularly, it relates to pipe hangers for supporting cooling pipes in hardening or refrigerating rooms.

In hardening or refrigerating rooms, difficulties arise in supporting the pipes which carry the cooling medium. It has been found that the ceilings of refrigerating rooms are likely to deteriorate very rapidly when in use. The cause of this troublesome defect is that the ceiling is subjected to extremes of temperature through the conduction of cold by the pipe supporting members. This is particularly true where the room above the hardening room is one in which high temperatures are present. The material of which the floor of the room above is made, being constantly heated and cooled, is likely to suffer serious damage. This is particularly true where metallic beams are used to support the hangers on which the cooling pipes are carried.

Secondly, these hardening rooms must be defrosted periodically. The coolness of the pipe supporting rods causes condensation in the ceiling structure. When the room is defrosted, this frozen condensation thaws out and is likely to cause serious inconvenience and to harm the ceiling construction. When it is refrozen, still further damage may occur.

A further disadvantage resides in the fact that heat is often conducted into the hardening room through the supports for the cooling pipes which thus lowers the efficiency of the room.

The principal object of my invention is to provide a pipe support and ceiling construction for hardening rooms in which the above disadvantages will not be present. Primarily, it is desirable to support the pipe hanger out of contact with the ceiling, particularly if this ceiling be of concrete, and out of contact with the beams by which the hanger is supported. This will avoid the chilling of the ceiling material and will prevent any condensation which might form on the rod from damaging the ceiling. Secondly, the construction will prevent the conduction of heat into the refrigerating room.

A further object is to support pipes in a relatively insulated condition without decreasing the strength or firmness of the supporting means.

In addition, my invention provides means for securing a pipe supporting rod immovably to a beam yet without any direct contact with the beam.

A final purpose is to support the upper end of a pipe carrying rod securely while insulating such

upper end both from the supporting beams and from the surrounding medium.

More specifically, my object is to provide pipe holding means extending through the ceiling of a refrigerating room hanging from a reinforcing beam in such ceiling but spaced from the beam by insulating material. In this respect, it is important that a part of the pipe holding means be above and vertically aligned with a part of the beam so that the intervening relatively weak insulating material will not be subjected to shearing action. Further, it is advantageous to have positive means for spacing the rod laterally from the beam.

Other objects and advantages of my invention will appear more fully from the following description when taken in conjunction with the accompanying drawings which form a part thereof.

In the drawings:

Fig. 1 is a vertical cross section through one form of the invention.

Fig. 2 is a top plan view of the same.

Figs. 3 and 4 are cross sections through modified forms of the invention.

The usual hardening room includes a concrete ceiling reinforced by steel beams or girders and a cork layer bonded to the lower side of the concrete.

In Fig. 1, the beams 2 serve as supports or reinforcements for a concrete ceiling 4 in which the beams are cast. A mass of cork 6 is bonded or cemented to the lower face of the concrete to insulate the room. A finishing layer 8 of suitable plastic material may be applied to the cork. Pipes 10 serve to conduct cooling fluid into and around the room and thus cool the room.

In order to support the pipes 10, I provide a cross beam 12 mounted between the beams 2 with its principal surface 14 arranged horizontally. This beam is provided at suitable intervals with openings 16.

A rod 18 is provided extending from within the room through the cork 6 and the opening 16. The lower end of this rod is provided with suitable means 20 for supporting pipes threaded thereon. The upper end of the rod is threaded, and a nut 22 engages the threaded portion. Below this nut is arranged a metal plate or disc 24 having a diameter greater than that of the opening 16 so that the disc partially overlies the horizontal portion 14 of the beam 12. Between the disc 24 and the beam 12 and surrounding the rod 18 is a disc 26 of cork or other insulating material preferably larger in diameter than the disc 24. A further disc 28 is provided around the rod 110

18 within and filling the opening 16, thereby preventing lateral movement of the rod and effectively insulating the same from the beam 12. The space between the beams 2 above and below the beam 12 is filled by large blocks 30, 32 of cork or other insulating material, thereby insulating the rod 18 even from the concrete 4.

Fig. 3 shows a modified form of ceiling in which no concrete is used. In this form, the cork ceiling is supported by staples 40 having their lower ends bent at an angle as at 42. The bends of these staples are engaged by hooks 44 on the ends of a rod 46 which extends across the top of and is supported by the beams 2. Otherwise this form of the invention is not different from that shown in Fig. 1.

Fig. 4 shows a second method of supporting a ceiling of the type shown in Fig. 3. In this modification, a plate or bar 50 rests on top of the beams 2. Each end of this plate supports one end of a bent bar 52 which extends into the cork 6 to support the same.

It will be noted that in each of the forms shown the rod 18 is insulated not only from the metallic supporting beams but also from the surrounding medium, whether it be air or concrete. It will also be evident that the disc 26 is not subject to shearing forces, and that there is a positive supporting action between the beam 12 and the disc 24 so that the pipes at no point depend on the tensile strength of insulating material for their support. It is plain that the rod 18 will not conduct cold from the refrigerating room into the ceiling or at least into the metallic and concrete parts of the ceiling structure. Chilling of these parts and damage to them by condensation is thus avoided. Additionally, no heat will be conducted through the rod 18 into the refrigerating room.

While I have described herein some embodiments of my invention, I wish it to be understood that I do not intend to limit myself thereby except within the scope of the appended claims.

I claim:

1. In a ceiling for a refrigerating chamber, a pair of spaced beams, a beam having a horizontal portion between said first beams and supported thereby, said horizontal portion having an opening therein, a cork ceiling below said first beams and supported thereby, a rod of less diameter than

said opening extending through and below said cork ceiling and through and above said opening, a cork disc larger than said opening mounted on said rod above said horizontal portion, a metallic disc larger than said opening on said rod above said cork disc, a nut on said rod above and engaging said metallic disc, a cork disc around said rod within said opening substantially filling said opening, and means on said rod below said ceiling to receive a pipe support.

2. In a ceiling for a refrigerating chamber, a pair of spaced beams, a beam having a horizontal portion between said first beams and supported thereby, said horizontal portion having an opening therein, a cork ceiling below said first beams and supported thereby, a rod of less diameter than said opening extending through and below said cork ceiling and through and above said opening, a cork disc larger than said opening mounted on said rod above said horizontal portion, a metallic disc larger than said opening on said rod above said cork disc, a nut on said rod above and engaging said metallic disc, a cork disc around said rod within said opening substantially filling said opening, a block of cork between said first beams above and around the upper end of said rod, a second block of cork between said first beams below said horizontal portion surrounding the portion of said rod between said horizontal portion and said cork ceiling, and means on said rod below said ceiling to receive a pipe support.

3. In a building construction, a pair of spaced beams, a beam having a flat portion between said first beams and supported thereby, said flat portion having an opening therein, a wall supported by said beams, a rod of less diameter than said opening extending through said opening, a disc of insulating material larger than said opening mounted on said rod on the opposite side of said flat portion from said wall, a metallic disc larger than said opening on said rod beyond said insulating disc, means on said rod engaging said metallic disc to prevent movement thereof longitudinally of said rod, and a disc of insulating material around said rod within said opening substantially filling said opening, said rod extending through said wall and beyond the surface thereof farthest from said beams.
